SAFETY ADAPTER SOCKET PLUG FOR
ELECTRICAL APPLIANCES

Hyman Shapiro, Brooklyn, N. Y.

Application March 28, 1949, Serial No. 83,806

2 Claims. (Cl. 173—334)

1

This invention relates to new and useful improvements in a safety adaptor incorporating a fuse of a desired type, for quick-detachable use either in connection with an electrical appliance or an electrical outlet, for plugging in either at a wall receptacle or the like or at an analogous receptacle carried by the appliance, whereby when there is a short circuit in any part of the appliance, said fuse blows, thereby to prevent the usual blowing of a fuse at a central location and the consequent breaking of current supply throughout an entire wiring system or throughout a subdivision thereof for supplying current not only at said outlet but otherwise throughout said subdivision; and, more particularly, the aim is to provide a novel and valuable such adaptor which is of exceptionally sturdy yet compact construction, which is easily assemblable and at very low cost, and wherein a blown fuse thereof may be readily removed and replaced.

A feature of the invention is the generally elongate nature of the new adaptor structure, adapting the same for easy manual handling, and convenient and desirable placement on an appliance; it being understood that by an appliance is meant not only such a utility as one having electrically operated movable parts, for instance, a vacuum cleaner, but also, for example, an electric iron, a lamp provided merely for illuminating purposes, etc., etc.

A further feature of the new adaptor is a simplified collection of metal or other conductive parts, these including a pair of input prong or blade terminals, a pair of outlet clip terminals, a connector element joining a first one of said clip terminals and a first one of said blade terminals and integral with both thereof, a further pair of conductive elements one leading from the second of said clip terminals and for contactive coaction with one end or terminal of the fuse and the other leading from the second of said blade terminals for contactive coaction with the other end or terminal of the fuse; and, in combination with these electrically conductive components, a simplified and improved single insulation-block mounting for them all.

A further feature of the invention is the provision of a simplified and improved protective outer casing or quasi-casing for said block, said casing moldable of insulation material; with the parts so relatively dimensioned and shaped that with said casing securely yet readily detachably in place on said block all electrically conductive elements, except said pair of blade terminals, are properly shielded and fully protectively enclosed.

2

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

10 Fig. 1 is a perspective view showing an embodiment of the invention as now favored, and looking toward the side thereof wherefrom are projected the aforesaid blade terminals.

15 Fig. 2 is a similar view, but looking at the side thereof at which are located two openings behind which are the mouth ends of said pair of clip terminals.

20 Fig. 3 is a perspective view bracketedly showing the adaptor as in Fig. 1 but with said casing removed, and showing also a standard electrical plug in course of being advanced toward having its blade terminals entered into the clip terminals of the adaptor.

25 Fig. 4 is a view like Fig. 3, except that with the parts here shown, the blade terminals of the adaptor are directed away from the observer rather than toward the observer as in Fig. 3; this view also showing the blade terminals of the adaptor in course of being advanced toward insertion in the receptacle of a wall outlet.

30 Fig. 5 is a perspective view, schematic in so far as is concerned merely showing in dot and dash lines of the main bulk of an insulation-block like that of the other views, but with here the prong terminals illustrated as projected from one end of said block and the clip terminals projected from the opposite end thereof.

35 Referring now to the drawings more in detail and first to Figs. 1-4, the adaptor illustrated is provided with a single readily moldable insulation-block 10, variously recessed over both its two opposite long sides, to provide a number of appropriate receptors for the already referred to conductive and contactive parts and the fuse.

40 The aforesaid pair of blade terminals are designated 11, and the aforesaid pair of clip terminals are designated 12; the fuse being indicated at 13 and as in the form of a well-known slender cylindrical unit sometimes called a cartridge fuse. As is well-known, this type of fuse has a central glass or otherwise transparent shell portion, capped at opposite ends by metal cups.

45 50 55 For quick mounting and detachment of this fuse in a recess 13a, which is of all the recesses present the one of greatest depth, there is pro-

jected, from one of the blade terminals 11 and into one end of said recess 13^a, a contact for one of the end cups of the fuse and constituted by a thin metal stamping 16 formed to include a pair of parallelly upstanding resilient jaws 16^a for releasably clasping said end cup; and into the other end of said recess 13^a there is projected a contact for the other end cup of the fuse and constituted by a thin metal stamping 17 formed to include a pair of parallelly upstanding resilient jaws 17^a for releasably clasping the end cup last-named.

The member 16 is apertured near its end remote from its jaws, and the near blade terminal 11 in Fig. 3 is matchingly apertured, so that through these apertures a single screw 18 may serve as shown for connecting the parts 11 and 16 as illustrated. As will be noted from the lower part of Fig. 3, a similar arrangement is provided, this including a single screw 19, for connecting the member 17 and the near clip terminal 12 in that view.

As shown best in Fig. 4, the near blade terminal 11 in this view has associated therewith a thin metal stamping 20 contactingly related to said terminal in a manner analogous to the relation of the stamping 16 to the other terminal 11, with the first two of the just mentioned parts connected together by a single screw 21. The same arrangement is provided near the bottom of the side of the block 10 seen in Fig. 4 by a thin stamping 22, like the stamping 20, with here again merely a single screw 23 being employed for connecting those parts. A recess 24, not as deep as, but otherwise similar to, the recess 13^a, is present in the block 10 and into which are inserted the end portions of the stampings 20 and 22 which are directed toward each other. Said recess 24 is laterally extended for accommodating a conductor member 25 for connecting stampings 20 and 22 by contact with their said end portions projected into the recess 24. Said conductor member 25 is here indicated as riveted in place, but in the space occupied by it there may be removably positioned, as by use of a screw or the like, a substitute unit comprising a plate-like member partially of insulating material, and partially carrying a fuse link for suitable contact at opposite ends with the end portions of the stampings 20 and 22 projected into the recess 24.

As best illustrated in Figs. 1 and 2, the insulation-block 10 equipped as just above described in connection with Figs. 3 and 4, may be provided with an easily removable fully protective casing, and of a kind to be fabricable at exceedingly small expense and from the use of low-cost molding dies; said casing designated 26. This casing, it will be noted, is in the main comprised of two like and parallelly spaced side walls 27 and 28, joined by a single integral bridging portion 29 substantially of frusto-triangular cross-section, this portion 29 being suitably cavitated at its near side and near its opposite ends for accommodation of the bight portions of the two clip terminals 12.

The openings 30, 30, seen at the left in Fig. 2, are located opposite the blade-terminal-receptor spaces between the reversely bent lengths of the clip terminals 12.

Merely two screws 31 and 32 suffice for securely yet readily detachably coupling the casing 26 fully protectively relative to the entirety of the adaptor as shown and described in connection with Figs. 3 and 4. Tapped recesses 33 and 34 would then be provided in the insulation block 10 for taking, respectively, the screws 31 and 32.

Thus, with or without the casing 26 in place, but, of course, preferably with the adaptor including such casing, the adaptor may be used as a plug at its blade terminal 11 in regard to such a wall receptacle as shown at 35 in Fig. 4, and then a standard plug 36, as one leading from an electrical appliance, may be inserted through the openings 30 for coaction of the blade terminals of said plug with the clip terminals 12 of the adaptor; or the adaptor may be applied at said appliance, by way of its blade terminals 11, and a plug like the plug 36 used in connection with the adaptor's clip terminals 12, with said plug wired to any direct or intermediate source of current supply.

Referring to the modification shown in Fig. 5, this differs essentially from the adaptor of Figs. 1-4, in that the adaptor of Fig. 5, with a single elongate insulation block 10' substantially like the block 10, so carries its two pairs of terminals that the two blade terminals 11' project from one end of said block and the two clip terminals 12' are at the other end of said block; the plug being of course recessed in accordance with the principles explained in connection with Figs. 3 and 4. In Fig. 5, the fuse is indicated 13', and the parts to which are applied reference numerals with primes added correspond, respectively, to the parts to which have been applied the same reference numerals without primes. Here, however, it will be noted, the jaws 16^a' are integral with one of the blade terminals 11', and the jaws 17^a' are integral with one of the clip terminals 12'. It will also be noted that these clip terminals are provided by a bending over of their stampings in a different manner from that characteristic of the clip terminals 12, that is, with the bights of the clip terminals 12' extending longitudinally of the stampings of which they are made.

The stamping used for providing one of the blade terminals 11' and the jaws 16^a' is somewhat Z bent as indicated at 31, to limit endwise movement of the fuse 13' in one direction; while, to provide a similar stop for said fuse against movement in the opposite direction, a small tongue 33 is struck from the stamping which includes the jaws 17^a' and one of the clip terminals 12'.

It will also be noted that here the other blade terminal 11' and the other clip terminal 12' are shown as integral parts of a single stamping. In that case, merely a single screw 39 would suffice securely to position said single stamping in the provided recess in a side of the block 10. As for the stamping 31, and the stamping including the tongue 33, these, together with the fuse 13', would be placed in the provided recess in the opposite side of the block 10'.

With a screw 40 used to fix the stamping 31 in position, the casing next referred to could provide a suitable recess therein for retaining the stamping which includes the tongue 33 properly in place in its portion of the recess last referred to. A single casing constructed according to the principles used in providing the casing 26 may be and desirably is included in an adaptor of the kind shown in Fig. 5.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new, and desire to secure by United States Letters Patent is:

1. In combination, an insulation block having transversely extended pairs of recesses in its opposed side faces and front and rear faces, said block having longitudinally extended recesses in each of its opposed side faces joining the recesses of each pair of recesses, elongated blade terminals positioned in one recess of each pair of recesses adjacent one end of said block and having end portions projected from the rear face of said block for insertion into an outlet receptacle, U-shaped clip terminals positioned in the other recess of each pair of recesses and having portions extended from the rear face of said block, said recesses housing said U-shaped clip terminals being open to the front face of said insulation block for insertion of the conductor blades of a plug to make electrical contact with said clip terminals, conductor means in said longitudinally extended recesses and connected between the respective blade terminals and clip terminals, a cover of insulation material closing said recesses retaining said blade terminals, said clip terminals and said conductor means in position in said recesses, said cover comprising walls extended along and co-extensive with the recessed side faces of said insulation block, a bridging element integrally formed with the rear edges of said walls and extended across the rear face of said insulation block, and means releasably securing said walls and bridging element to said insulation block, said bridging element being narrow and located to extend over and cover the portions of said clip terminals which project from the rear face of said insulation block.

2. In combination, an insulation block having transversely extended pairs of recesses in its opposed side faces and front and rear faces, said block having longitudinally extended recesses in each of its opposed side faces joining the recesses of each pair of recesses, elongated blade terminals positioned in one recess of each pair of re-

cesses adjacent one end of said block and having end portions projected from the rear face of said block for insertion into an outlet receptacle, U-shaped clip terminals positioned in the other recess of each pair of recesses and having portions extended from the rear face of said block, said recesses housing said U-shaped clip terminals being open to the front face of said insulation block for insertion of the conductor blades of a plug to make electrical contact with said clip terminals, conductor means in said longitudinally extended recesses and connected between the respective blade terminals and clip terminals, a cover of insulation material closing said recesses retaining said blade terminals, said clip terminals and said conductor means in position in said recesses, said cover comprising walls extended along and co-extensive with the recessed side faces of said insulation block, a bridging element integrally formed with the rear edges of said walls and extended across the rear face of said insulation block, and means releasably securing said walls and bridging element to said insulation block, said bridging element being narrow and located to extend over and cover the portions of said clip terminals which project from the rear face of said insulation block, said bridging element having cavities in its inner face into which the projected portions of said clip terminals extend.
